(57) **CLAIM**

The ornamental design for an inhaler, as shown and described.

DESCRIPTION

FIG. 1 is a right side elevation view of the inhaler, showing my new design;

FIG. 2 is a front elevation view thereof;

FIG. 3 is a left side elevation view thereof;

FIG. 4 is a rear elevation view thereof;

FIG. 5 is a top plan view thereof;

FIG. 6 is a bottom view thereof;

FIG. 7 is a right side, front perspective view thereof;

FIG. 8 is a right side elevation view showing the inhaler in an alternate (open) position;

FIG. 9 is a front elevation view thereof;

FIG. 10 is a right elevation side view thereof;

FIG. 11 is a rear elevation view thereof;

FIG. 12 is a top plan view thereof;

FIG. 13 is a bottom view thereof; and,

FIG. 14 is a side, front perspective view thereof, showing the inhaler in the open position.

1 Claim, 6 Drawing Sheets
